UNITED STATES PATENT OFFICE.

ROBERT H. WEIR, OF PHILADELPHIA, PENNSYLVANIA, ASSIGNOR OF ONE-HALF TO JAMES S. WHITE, OF CAMDEN, NEW JERSEY.

DUMMY-HEAD.

SPECIFICATION forming part of Letters Patent No. 246,929, dated September 13, 1881.

Application filed June 9, 1881. (No model.)

To all whom it may concern:

Be it known that I, ROBERT H. WEIR, of the city and county of Philadelphia and State of Pennsylvania, have invented a new and useful Improvement in the Manufacture of 5 Dummy-Heads, of which the following is a specification.

My invention consists in forming the head of a dummy for exhibiting garments, &c., of 10 one piece of leather worked over a mold or cast in relief, the leather being cut in a proper shape, so as to prevent wrinkling.

In the accompanying drawings, forming part 15 of this specification, and in which similar letters of reference indicate like parts throughout the several views, Figure 1 shows the form or shape of the pattern after which the covering material is to be cut. Figs. 2 and 3 represent a side and back view of the completed head, 20 and Fig. 4 shows a section of the neck of the mold or cast over which the leather is to be worked.

Fig. 1 shows a piece of leather cut to a suitable size and shape to cover the head shown 25 in Figs. 2 and 3. This piece of leather has its edges skived or beveled, as shown by the dotted and broken lines, the dotted lines indicating that the skiving is done on the upper side and the broken lines that it is done on 30 the under side of the covering material. This skiving is done so that there will be no rough joints when the projecting ends of the pattern are lapped one over the other in the completed head.

35 In Figs. 2 and 3 are shown the joints which would be formed by using the pattern shown in Fig. 1.

In covering the head the leather is first soaked 40 in glue in order that it may become flexible and readily take and retain the shape of the mold or cast. After the leather has been thoroughly soaked it is applied to the mold in the following manner: The face is first covered, particular care being bestowed upon covering the nose 45 K. At K, in Fig. 1, is shown the manner in which the leather is cut so as to cover the nose. The chin and front part of the neck are next covered by that part of the pattern designated by I, Figs. 1 and 2; one side and part of the 50 back of the neck by H, Figs. 1, 2, and 3. This overlaps one side of I. The upper part of the head is now covered with that part of the pattern represented by D, Fig. 1. The part E,

Figs. 1, 2, and 3, is now drawn into its place and overlaps one side of D. The back of the 55 head is next partly covered by A, Figs. 1 and 3, which overlaps the under edges of E and D. G is now drawn over and F is put into place, covering the upper edge of G, as shown in Figs. 2 and 3. B is next put into position, 60 and C is placed over its lower edge, as shown in Figs. 2 and 3, completing the head. To make the leather conform perfectly to the shape of the mold or cast it is, after being applied to the head, carefully rubbed or smoothed all 65 over with a smooth piece of bone or ivory. To prevent the leather sticking to the mold it is covered with paper or other material impervious to glue. After the head is dry it is finished in the usual manner by painting in a proper 70 way.

It being impossible to withdraw an ordinary mold or cast when the head is finished, I make use of the device shown in Fig. 4, which represents a section of the neck of a mold or cast 75 made of several pieces, in the present case five.

The center piece or key being as large as it can conveniently be made, it will readily be seen that when this key is withdrawn the mold will fall to pieces and the remaining parts 2, 80 3, 4, and 5 be withdrawn with perfect ease.

I am aware that dummy-heads have before been made of leather, but they have never before, to the best of my knowledge, been made of one piece.

In Letters Patent No. 223,419, granted to me January 6, 1880, and assigned to Samuel Goodman and David Myers, of Philadelphia, heads are made of several pieces of leather arranged in two sets, one for the face and one for the 90 back, the two sets afterward being secured together by sewing over the seam a piece of leather. In my present invention I do away with this and make the heads of one piece only.

What I claim, and desire to secure by Letters Patent, is—

A dummy-head composed of one piece of leather formed of the pattern having the configuration described and shown, its different projecting ends brought together, shaped, and secured substantially as and for the purpose described.

ROBERT H. WEIR.
